CHAIN LINK

Filed Dec. 17, 1923

UNITED STATES PATENT OFFICE.

LOUIS A. VEIGEL, JR., OF NEWARK, NEW JERSEY.

CHAIN LINK.

Application filed December 17, 1923. Serial No. 681,140.

This invention relates to improvements in chain links and more particularly to small ornamental links as used in the construction of watch chains and the like.

5 One of the objects of the invention is to provide a neat and attractive link embodying a new design and construction.

A further aim is in the provision of means combined with the link whereby different 10 colors may be disclosed through the interstices in the wall of the links which are hollow and connected by swivel joints.

These several objects, and others of a similar nature, are accomplished by the 15 novel design, construction and arrangement of parts hereinafter described and shown in the accompanying drawing, forming an essential part of this disclosure, and in which:—

20 Figure 1 is a plan view of the flat blank from which the main portion or body of the link is formed.

Figure 2 is a collective view showing plan and edge elevations of the chain eye blank 25 and finished article prior to assembly.

Figure 3 is a longitudinal sectional view of a link as completely assembled, drawn to an enlarged scale.

Figure 4 is a collective view, showing in 30 side elevations the parts in detail preparatory to assemblage.

Figure 5 is a transverse sectional view taken on line 5—5 of Figure 3.

Figure 6 is a side elevational view of a 35 completed link, parts being broken away to disclose the interior.

Figure 7 is a side elevational view of one form of a finished link.

Figure 8 is a similar view showing a 40 modification of the same.

Figure 9 is another like view showing the same or a similar link as further modified.

Referring more in detail to the drawing, 45 the blank, shown in Fig. 1 is substantially rectangular in outline, made of any preferred metal and of such proportions as may be preferred.

This blank is pierced to produce a plural- 50 ity of openings 10, which may be plain or otherwise as desired, preferably elongated as shown, presenting solid ends 11 and a central portion 12, the longitudinal edges having recesses 13, forming, when the blank 55 is coiled into cylindrical shape, uniform spaces equivalent to the openings 10, these

openings being bounded by the elements 11 and 12 and longitudinal bars 14.

The eyes or link connectors are die cut to form circular blanks 15, having stems 16, 60 the blanks having openings 17 formed in them and then pressed to present eyes 18 of circular cross section, as are also the finished stems 19.

Each link is provided at its ends with 65 caps consisting of cylindrical bands 20, tight fitted to the ends of the links and secured by solder thereover; each band has an integral head 21 having a central opening suited to receive the stem 19, which after 70 being passed through, is upset to form a head 22.

While the eyes 18 may be rigidly fixed in the caps, it is deemed preferable to permit the stems to swivel in the openings, thus 75 allowing the chain to readily adjust itself.

The foregoing describes in general the preferred type of construction, the completed article being in effect a cylinder having open panels in its walls, the cylinder 80 having rigid caps in which swivel eyes are secured.

As shown in Figure 6 the cylinder may have a lining 23, as colored glass, another metal of different color or other inner element which can be seen through the openings 10.

Figure 7 shows one type of ornamentation in which the bars 14 are curved inwardly from all sides presenting necks or reduced 90 portions 24 of pleasing appearance.

Another style of ornamentation is disclosed in Figure 8, in which one end of the link is rotated slightly with respect to the opposite end, producing a twisted effect on 95 the bars 14, as at 25; this twisted condition is carried to a greater extent, as indicated at 26 in Figure 9.

The foregoing disclosure is to be regarded as descriptive and illustrative only, 100 and not as restrictive or limitative of the invention, of which obviously an embodiment may be constructed including many modifications without departing from the general scope herein indicated and denoted 105 in the appended claim.

Having thus described my invention, what I claim as new and desire to secure by Letters Patent, is:—

An ornamental chain link comprising a 110 cylinder having a series of equally spaced, longitudinally disposed elongated openings

in its wall, forming a series of longitudinal bars, said bars being arranged in circumferential rows, each of said series divided by a blank central portion, said bars being twisted axially to produce distortion, caps fixed on the ends of said cylinder, connecting elements having swivel stems secured

in said caps and a lining of contrasting color disposed within the said cylinder and being visible to said openings.

This specification signed and witnessed

10 this 14th day of December, 1923.

LOUIS A. VEIGEL, JR.
